UNITED STATES PATENT OFFICE

OLE HOVE, OF ATASCADERO, CALIFORNIA

MOTOR-CONTROLLING MEANS

Application filed March 15, 1928. Serial No. 262,022.

The invention relates to automatic controlling means for the driving motor of a machine embodying a work performing member, a work support movable toward and from 5 said member, and a power controlling device for the motor having a control member movable from one position at which the motor merely "idles," to another position at which the power of the motor is increased for work 10 performing.

One illustration of such a machine is a buzz-saw for cord wood and the like, in which the "work performing member" is the saw; the "work support", the pivoted or slidable 15 table; the "motor", a gasoline engine; its carbureter, the "controlling device"; and the throttle valve, the "control member".

It is the principal object of the invention to provide novel and efficient means controlled 20 by movement of the work support, for so operating said control member as to automatically increase the power of the motor as said work support advances the work to the work performing member, and to restore said 25 motor to "idling" when the work has been performed. In the saw herein disclosed, the motor speed is increased automatically each time a cut is made and after making such cut, it again "idles" until the next cut is to 30 be made.

With the foregoing in view, the invention resides in the novel subject matter hereinafter described and claimed, description being accomplished by reference to the accompanying 35 drawings.

Fig. 1 is a side elevation partly broken away and in section showing a buzz-saw embodying the invention, the parts being in such positions that the motor merely "idles".

Fig. 2 is a view similar to Fig. 1 but showing the pivoted table advanced and the throttle valve positioned for increasing the speed and consequently the power of the motor.

Fig. 3 is a detail view similar to Fig. 2 but 45 showing the manner in which the throttle valve is restored to "idling" position, as soon as the work-supporting table starts on its return movement.

Fig. 4 is a perspective view of a number of 50 parts of the present invention.

Fig. 5 is a detail sectional view on line 5—5 of Fig. 4.

Fig. 6 is a top plan view showing a different form of saw embodying the invention.

Fig. 7 is a view similar to Fig. 1 but illustrating a modified construction of the throttle valve controlling means.

The form of construction shown in Figs. 1 to 5 will first be described.

The numeral 8 denotes the frame of a 60 portable buzz-saw mounted on appropriate wheels 9. This frame carries a driving motor 10 for the saw 11, and a table 12 is pivotally mounted at 13 for movement toward and from the saw. 14 denotes the carburetor of the 65 motor 10, and 15 has reference to the throttle valve which always occupies a "motor idling" position when the saw is not performing work. In carrying out my invention, however, I make novel provision for automatically moving the throttle valve to increase 70 the power of the motor when the table 12 is advanced to present the work W to the saw.

16 denotes a curved track concentric with the pivot 13, secured at one end to the table 75 12, as denoted at 17, and projecting forwardly from said table, the advance end of said track being provided with a cam 18. 19 has reference to a spring arm which is stationary with respect to the track 16 and the table 12, said 80 track being normally in rear of said spring arm as shown in Fig. 1. This arm extends in the same general direction as the track 16, is suitably anchored at one of its ends as denoted at 20, but is free at its other end. 85 Fulcrumed between its ends at 21, on the free end of the spring arm 19, is a short lever 22 whose lower end constitutes a shoe 23, co-operable with the track 16, the upper end of this lever being connected by a link 24 with 90 the throttle valve 15.

When the parts stand as in Fig. 1, the shoe 23 stands in the path of the cam 18, so that upon inward movement of the table 12, said cam and shoe will contact with each 95 other, the lever 22 being then held against any swinging movement under the influence of the cam, by a shoulder or the like 25. The result is that the cam 18 effects upward shifting of the lever 22 and the link 24 as a sin- 100

gle unit, during which movement, upward swinging of the arm 19 takes place. This upward movement of parts opens the throttle valve and increases the power of the motor as the work W is advanced to the saw 11. 5 As long as the carriage 12 is forced inwardly, the shoe 23 remains upon the track 16, in such position as to hold the throttle valve open. Just as soon as the outward movement of 10 the table 12 starts, however, the lever 23 is rocked away from the shoulder 25 and the spring 19 comes into play to move the parts downwardly to completely move the throttle valve 15 to "motor idling" position, 15 as seen in Fig. 3. As soon as the track 16 clears the shoe 23, the spring 19 which is still under some degree of tension, pulls downwardly upon the lever 23 and restores it to the upright position shown in Fig. 1 20 in readiness for operation the next time the carriage or table 12 is forced toward the saw. Thus, each time this carriage or table is moved to advance the work to the saw, the power of the motor 10 is automatically in- 25 creased, and as soon as said carriage or table starts outwardly, the motor is restored to "idling". Thus, proper control of the motor is effected without the necessity of any governor and the results obtainable are better than those attained by the use of such a governing device.

In the preferred form of construction, the details shown most clearly in Fig. 4 and 5, are employed. In these views, 26 denotes a 30 metal plate secured by bolts 27 to the free end of the spring arm 19, said plate having ears projecting upwardly and longitudinally therefrom, said ears being denoted at 28. The lever 22 is received between these ears 35 and is preferably formed from a plate of substantially the same construction as the part 26.

In Fig. 6, a slidable carriage or table 12^a such as those commonly used on slidable table saws is provided for advancing the work to the saw 11^a, the latter being driven by a motor 10^a whose carburetor is denoted at 14^a, and the throttle valve at 15^a. 16^a denotes a track on the table or carriage 12^a, having a cam 18^a at its advance end, and D denotes a device constructed and operating in the same manner as the parts 19—22—23—25—24, above described. 24^a however denotes a link or rod of greater length than the link 24 but suitably connected with the throttle valve 15^a. This rod preferably carries a nut 29 co-operable with a stop 30 to act as adjustable limiting means for the return or closing movement of the throttle valve.

60 In Fig. 7, the parts 10^b, 11^b, 12^b, 14^b, 15^b, 16^b and 18^b correspond to the similarly numbered portions of Figs. 1, 2 and 3. The throttle valve 15^b however, is connected by an adjustable link 31, with a lever 32 which is 65 fulcrumed between its ends at 34 upon a suit-

able support. Pivoted upon the end of this lever toward the track 16^b is a member 35 whose lower end 36 constitutes a shoe for co-action with the cam 18^b and the upper edge of the track 16^b. A stop 37 is provided 70 to prevent the member 35 from swinging about its pivot when the cam 18^b forces against said member, so that swinging of lever 32 will then be effected to open the throttle valve. The valve remains open as long as the table or the like 12^b is being advanced, but as soon as this table is reversed, member 35 is swung about its pivot and lever 32 is restored to "motor idling" position, by an appropriate spring 38. 75

When adapting the invention to one kind of saw or another, the details herein disclosed are preferably followed. However, it will be understood that the invention is applicable also to other kinds of machines and that within the scope of said invention as claimed, numerous variations may be made. 80

I claim:—

1. In a machine having a work performing member, a work support movable toward and from said member, a motor connected with said member for driving the same, and a power controlling device for said motor having a control member movable from a normal "motor idling" position to a power increasing position; means actuated by said work support for moving said control member automatically to said power increasing position upon advancement of said work support toward said work performing member and for automatically restoring said control member completely to said "motor idling" position upon initial return movement of said work support. 95

2. In a machine having a work performing member, a work support movable toward and from said member, a motor connected with said member for driving the same, and a power controlling device for said motor having a control member movable from a normal "motor idling" position to a power increasing position; a track carried by said work support and extending in the direction of movement thereof, a shoe substantially stationarily mounted with respect to said track but mounted for movement to one position under the influence of said track upon advance of the work support and track and to another position upon return of said work support and track, and means operatively connecting said shoe with said control member for transmitting motion from one to the other, whereby to increase the power of the motor immediately upon work advancement and to restore said motor to "idling" upon initial work retraction. 110

3. In a machine having a work performing member, a work support movable toward and from said member, a motor connected with said member for driving the same, and a 115

power controlling device for said motor having a control member movable from a normal "motor idling" position to a power increasing position; a track carried by said work support and extending in the direction of movement thereof, a spring arm stationarily mounted with respect to said track, said arm being disposed near and extending in the same general direction as said track, said arm being secured at one end and free at its other end, a short lever transverse to said arm and fulcrumed to said free end thereof, said lever having one end positioned to be struck by the advance end of said track, said track end being provided with a cam for bodily moving the lever and springing said arm away from the track, means for preventing swinging of said lever when forced by said cam, but for permitting free swinging of said lever upon reverse movement of said track, and connecting means between said lever and said control member for utilizing the cam-affected movement of the former to move said control member to power increasing position and for utilizing the track-affected swinging of the lever to restore said control member to said "motor idling" position.

In testimony whereof I have hereunto affixed my signature.

OLE HOVE.
